PORTABLE LARGE ROLL PAPER HOLDER
AND CUTTER

Stanley J. Bina, Grand Forks, N. Dak.

Application July 20, 1951, Serial No. 237,755

2 Claims. (Cl. 242—55.5)

1

This invention relates generally to paper roll holders and cutters, and more particularly to such devices of the portable type, adapted to handle the larger size paper rolls in warehouses, grain elevators, flour mills, furniture factories and others that require portability especially over a large area.

Warehouses, public and private, that require 48 inch and 60 inch and 72 inch width heavy kraft paper for wrapping and packing must carry the roll of paper to where it is needed, and this may involve a distance from 50 feet to 200 or more. For example, a 72 inch roll of kraft with a standard 9 inch diameter weighs about 105 to 110 pounds. A 15 inch diameter roll weighs around 325 to 350 pounds. It is impractical and wasteful to attempt to carry these rolls to where they are needed, because their use is required in different parts of the warehouse and that varies from day to day depending on what type of commodity is to be packed. My portable paper rack and cutter can be easily handled by one person even with the 350 pound roll. This saves time and effort, expense and a saving of manpower and lends itself to more efficiency in any type of business where heavy rolls of paper are used.

In a grain elevator, each car is lined with kraft paper, a 72 inch roll being generally used because that is the height of the grain car door and grain loading height inside the car. One man can easily roll my holder and cutter to the base of operation (inside the car), and tear off as many pieces of paper as required for the job, and it is finished. On the other hand, the old way is to walk into the elevator, tear off a few feet, then go back for another, and so on, which often requires several trips and in some cases where the box car is in poor repair, it requires several trips, as many as 15 to 20 trips back and forth. Flour mills have much the same problem except they have more area to cover and consequently more carrying back and forth of paper.

Furniture factories especially have large floor areas and paper is used all over, and further my portable apparatus will cut down handling and a definite saving on paper because only what is actually needed is conveniently torn off.

To obviate such present inefficient and unsatisfactory operation, is one of the objects of this invention, in providing a portable holder and cutter, adapted to handle efficiently such large rolls of paper, and other objects and advantages will be apparent from the following description and claims, together with the accompanying drawings.

2

In the drawings:

Fig. 1 is a side view of my invention in the vertical position.

Fig. 2 is a side view of my invention in its horizontal position.

Fig. 3 is a section on the line 3—3 in Fig. 1.

Fig. 4 is a detail of the upper part of my invention, partially in section, to show upper mounting thereof.

Fig. 5 is a section on the line 5—5 in Fig. 1.

Fig. 6 is a detail of the lower part of my invention, partially in section, to show the lower mounting thereof.

Fig. 7 is a section on the line 7—7 in Fig. 4.

Referring to the drawings, the main frame of my invention comprises a rigid, tubular rod 10, preferably welded at one end 11 to a base plate 12, and also preferably welded to the base plate's integral, right-angled-turned flange 13, which in turn is secured to bracket 14, and mounted, for portable use, on axle 15 and casters 16. The base 12 is preferably of square or slightly rectangular shape, as shown, and of sufficient strength and dimensions to support the weight of a roll of paper 17, mounted thereon. The rod 10, which may be of any suitable dimensions, such as one-inch outside diameter and one-eighth inch wall, to combine strength and lightness, is shown welded to a center of a side edge of base 12, and 30 also welded to the side flange 13 thereof, on which latter the axle and casters are attached, as above mentioned. Brace rods 18, welded at 18' near the lower end of rod 10, extend outwardly at suitable angles, to be welded at 19, to base 12, so as to maintain such rod 10 and base 12 rigidly perpendicular to each other. Secured near the opposite end of rod 10 is a floor-rest bracket 20, preferably of triangular shape, with apex 21 of the triangle secured to rod 10, and with legs 22 and 23 of the triangle extending outwardly to base 24, thus cooperating with casters 16, in making rod 10 lie substantially horizontal when in position shown in Fig. 2.

As shown more in detail in Fig. 6, a disc 25 has a central integral stud 26 projecting downwardly through an aperture in base 12, and a nut 27 is adapted to be threaded thereon, to prevent withdrawal of the stud upwardly, and yet permit rotation of the disc 25 relative to the base 12, it being understood that the paper roll 17 rests upon, and rotates with, disc 25. Near the opposite end of rod 10 and slidable thereon, is a collar 28, formed by the wrapped-around end of paper-roll brace 29, preferably made of strap metal, and 55 having its opposite end 29' wrapped around and

preferably welded to pin 30, which is formed with a conical end 31 to fit in the upper end 32 of the core 33 of paper roll 17, when the opposite end 34 of the core fits over the upwardly projecting pin 35 on disc 25.

A handle 36 is formed on the upper end of rod 10, and a thumb nut 37 is provided to lock collar 28 in position, after being slid up on rod 10, to permit mounting of the paper roll 17 between upper pin 31 and lower pin 35, at opposite ends of the paper roll. A bolt 38 may be used to rigidly secure together the bracket arm 29 and the pin 30. At spaced intervals, hinged metal straps 39 project outwardly from rod 10, to support a swinging rod 40, which in turn carries spaced metal straps 41, the outer ends of which, 42, are secured to cutter blade 43. Each of such hinged metal straps 39 comprises two arms 44 and 45, pivoted together at 46, with arm 44 rigidly secured to rod 10, and arm 45 loosely rotatable about rod 40, and pivoted at 46 to the outer end of arm 44. For urging cutter blade 43 into contact with the paper roll 17, wire springs have ends 47 secured to rod 40, and opposite ends 48 pressing against respective faces of straps 41. As a supplemental connection between rods 10 and 40, near the center of each, a single bracket arm 49 is curved to fit around the periphery of the paper roll 17 and has one end formed with collar 50, loosely encircling rod 10, and the other end formed with a collar 51, to encircle rod 40, and a wing nut 52 locks collar 51 in adjusted position. The cutter blade 43 is preferably long enough to overlie, and cut paper from, the longest paper roll 17 adapted to be supported between the ends of frame rod 10, while the swinging rod 40 can be slightly shorter, as shown, than either the cutter blade 43 or the rod 10, so long as it properly supports the cutter blade in operative position.

In use of my invention, collar 28 is un-clamped and slid upwardly on rod 10 sufficiently to permit a roll of paper to be inserted into operative position, by seating the lower end of the paper core on pin 35, and then sliding the upper pin 31 down into the upper end of the paper core. The bracket arm 49 is adjusted to hold the swinging rod 40 and cutter blade 43 in functional relation to the paper roll. The entire device, thus loaded at a convenient paper-roll-storage station, is then wheeled into the railroad car to a spot convenient to where needed for use, and the roll of paper, with its supporting disc, then rotated, and a piece of paper un-wound to the length desired, and then cut off against the sharp edge of the

cutter blade. After such cut-off piece of paper has been applied, additional pieces can be obtained, and the entire device rolled elsewhere.

Having illustrated and described my invention, I claim:

1. In a paper holder and cutter, the combination of a main frame rod, a frame base secured to said frame rod and adapted to support a roll of paper, a swinging rod, means for supporting said swinging rod from said frame rod, said supporting means comprising a plurality of spaced arms, each of said arms being formed by link members having their respective inner ends pivoted together, and their outer ends pivoted respectively to said frame rod and swinging rod, a cutter bar, and means for supporting said cutter bar from said swinging rod, said last-named supporting means comprising a plurality of spaced arms, each of said last-named arms having one end secured to the cutter bar and the opposite end pivoted to the swinging bar, means for urging said cutter bar toward the roll of paper, said urging means comprising a wire spring having one end secured to the swinging rod and the other end pressing on the face of said last-named arm.

2. In a paper holder and cutter, the combination of a main frame rod, a frame base secured to said frame rod and adapted to support a roll of paper, a swinging rod, means for supporting said swinging rod from said frame rod, said supporting means comprising a plurality of spaced arms, each of said arms being formed by link members having their respective inner ends pivoted together, and their outer ends pivoted respectively to said frame rod and swinging rod, means for supporting said cutter bar from said swinging bar, means for urging said cutter bar toward said roll of paper, and a supplemental bracket arm having its ends pivoted respectively to said frame rod and swinging rod.

STANLEY J. BINA.
